FIG. 1 is a plan view of a link type floor mat broken away along the dotted lines to show the four corners and disclosing my new design;

FIG. 2 is a top plan view of one link of the floor mat shown in FIG. 1;

FIG. 3 is a front view in elevation of the link shown in FIG. 2;

FIG. 4 is an end view in elevation of the link shown in FIG. 2;

FIG. 5 is a fragmentary vertical sectional view taken along the line 5—5 of FIG. 1 and shown on an enlarged scale;

FIG. 6 is a plan view of a modified form of a link type floor mat broken away along the dotted lines to show the four corners;

FIG. 7 is a top plan view of one link of the floor mat as shown in FIG. 6;

FIG. 8 is a front view in elevation of the link shown in FIG. 7;

FIG. 9 is an end view in elevation of the link shown in FIG. 7; and

FIG. 10 is a fragmentary vertical sectional view taken along the line 10—10 of FIG. 6 and shown on an enlarged scale.

This application is a continuation of my co-pending applications Serial Nos. D. 61,905 filed August 26, 1960 and D. 62,631 filed October 26, 1960, and now abandoned.

I claim:

The ornamental design for a link type floor mat, as shown and described.
